Claims priority, application France Apr. 17, 1958

9 Claims. (Cl. 167—87.1)

This invention relates to processes for the permanent waving of hair and to novel compounds useful in such processes.

The most common processes for the permanent waving of hair ordinarily comprise a first step in which the hair is impregnated with an aqueous solution containing one or more sulphhydryl compounds, such for example as mercaptoalkanoic acids, employed as reducing agents for the $-\text{S}-\text{S}-$ linkages of the keratin, in order to impart the hair the desired plasticity so as to permit reshaping.

While kept in the form of aqueous solutions, the aforesaid compounds which contain a free $-\text{SH}$ group tend to decompose and to evolve hydrogen sulphide and other products of disagreeable odour. Of these compounds, only thioglycollic acid is used in practice.

In order to obviate the aforesaid disadvantages, it has already been proposed to block the $-\text{SH}$ group of these mercaptoalkanoic compounds by substituting for the hydrogen atom another group which can be readily eliminated by simple hydrolysis in alkaline medium. Thus, French Patent No. 999,436 proposes the use of compounds of the general formula:

in which R represents a hydrogen atom or an alkyl group, and X an amino, alkyl, or alkoxy group. However, such compounds are not well adapted to standard practice, since, in order to obtain hydrolysis of the alkaline solution and to make it ready for use, it is necessary to heat it to about 95° to 100° C. and then to have it cooled. It is not possible to effect the hydrolysis of such compounds after their application to the hair since the quantity of alkali, e.g. ammonia, necessary to achieve the hydrolysis, at the beginning thereof, causes the solution to exceed the narrow operative pH limits (from 9 to 9.8) within which the liberated thioglycollic acid derivative is effective without being a depilatory.

There have also been employed, in the first step of permanent waving, amides of thioglycollic acid having the general formula $\text{HSCH}_2\text{CONHR}$, where R is hydrogen, a lower alkyl residue or a lower hydroxylalkyl residue. However, while the latter type of amide gives good results in a fairly wide pH range (from 6 to 9), in regard to the quality of the wave obtained, such amides have the major disadvantage of being more unstable than thioglycollic acid. Accordingly, they more readily liberate, on storage, a quantity of hydrogen sulphide such that the product becomes substantially unusable. Moreover, they tend to produce lesions on the hands of operators who repeatedly use them.

It is possible to avoid or minimise the disadvantages inherent in these amides, while retaining the possibility of obtaining a good wave, by using, for softening the keratin of the hair, S-acyl derivatives of these amides, said derivatives being novel chemical compounds per se.

2

According to a first object of the present invention there are provided novel compounds suitable for use for the softening of the keratin of the hair and having the general Formula I:

in which R represents a lower alkyl or carboxyalkyl residue, and R₁ and R₂ each represent a hydrogen atom or a lower alkyl residue.

A further object of the invention is a process for the so-called permanent waving of hair wherein the hair is impregnated with an aqueous solution of a mercapto compound, constrained to a desired configuration and set in that configuration, wherein the mercapto compound used is an amide of general Formula I.

Aqueous solutions of S-acyl-mercaptopropanoamides according to the invention contain substantially no free $-\text{SH}$ groups, but they undergo hydrolysis in the presence of ammonia, an organic base such as an ethanamine, e.g. triethanolamine, or even an inorganic base, to give mercaptoamides useful as softening agents for the keratin, the hydrolysis being promoted by heating. This hydrolysis, on which the permanent waving process of the invention is framed, has been carefully studied.

It has been found that, either as a function of the concentration of the base employed, or as a function of the temperature at which the hydrolysis is carried out, or again as a function of these two factors together, the degree of hydrolysis obtained varies within wide limits, and may even reach the theoretical (e.g. maximum) value in some cases, within an extremely short period of time, for example one minute.

Such a high rate of hydrolysis has made it possible to use the said compounds quite conveniently under various conditions of application, as hereinafter explained.

The following tables show the percentage of hydrolysis obtained under various conditions:

TABLE I

Hydrolysis of aqueous alkaline solutions of S-acetyl-mercaptopropanoamide

50	Hydrolytic agent	Concentration of the product in gram mol/l.	Concentration of the base in gram mol/l.	Time, min.	Percent Hydrolysis		Final pH-value
					1	20	
Ammonia.....		0.7	1.2		70	88	8.4
55	Monethanolamine	0.7	0.9	1	72	82	9.2

A—AMBIENT TEMPERATURE

60	Hydrolytic agent	Concentration of the product in gram mol/l.	Concentration of the base in gram mol/l.	Time, min.	Percent Hydrolysis		Final pH-value
					15	15	
65	Ammonia.....	{ 0.5 0.5	0.5 1		70	98	8.1 8.8

B—TEMPERATURE OF 40° C.

60	Hydrolytic agent	Concentration of the product in gram mol/l.	Concentration of the base in gram mol/l.	Time, min.	Percent Hydrolysis		Final pH-value
					15	15	
65	Ammonia.....	{ 0.5 0.5	0.5 1		70	98	8.1 8.8

The data obtained with S-acetyl-N-methyl-mercaptopropanoamide and S-acetyl- α -mercaptopropionamide are similar to those set forth in Table I under the same experimental conditions.

TABLE II

Hydrolysis of S-succinyl mercaptoacetamide (S-β-carboxypropanoyl-mercaptoacetamide)

A—AMBIENT TEMPERATURE, USING AMMONIA AS HYDROLYTIC AGENT

Concentration of the product gram mol/l.	Concentration of NH ₃ in gram mol/l.	Time, min.	Percent Hydrolysis	Final pH-value
0.65	0.65	1	20	5.9
0.65	0.65	20	20	5.8
0.65	1.30	1	58	8.9
0.65	1.95	1	92	9.2
0.65	1.95	20	100	8.9

B—TEMPERATURE OF 50° C.

Concentration of the product gram mol/l.	Concentration of NH ₃ in gram mol/l.	Time, min.	Percent Hydrolysis	Final pH-value
0.65	0.65	20	30	4.8
0.65	1	20	58	5.9
0.65	1.20	20	89	7.7

It will be seen from these data that the said products permit, by their alkaline hydrolysis, the production of aqueous solutions containing the corresponding mercapto-amides at different concentrations and pH values, and such solutions may be selected in dependence upon the desired result.

It should be noted that, more especially in the case of the use of S-succinyl-mercaptoacetamide, that it is even possible, by a suitable adjustment of the quantity of the base employed, to obtain an aqueous solution of mercaptoacetamide of an acid pH value.

Accordingly, the present invention further includes compositions suitable for softening hair, as a step in the permanent waving, comprising in aqueous solution a compound of general Formula I and an alkalizing agent, particularly ammonia or an ethanolamine.

The ability of the compounds of general Formula I to give the desired mercaptoamides readily and in good yields may be utilised in practice to obtain a permanent wave in accordance with the various methods herein-after briefly described.

Thus, in accordance with a first embodiment of the process of the invention, there is applied to the hair an aqueous solution prepared at the time of use, by simply dissolving the compound of general Formula I in powder form in the desired quantity of water containing the calculated quantity of the base. Such solutions can be employed in the usual manner for the permanent waving of hair.

In accordance with a second embodiment of the same process, the hair may be impregnated with a non-alkaline aqueous solution of one of the aforesaid compounds and then, after winding the hair on curlers, the hair may be saturated with an appropriate alkaline solution. In this case, the liberation of the various mercaptoacetamides takes place on the hair itself.

Various waving methods may be employed in accordance with the temperature at which it is desired to apply the process. Thus, for example, a so-called cold wave may be effected at room temperature, a permanent wave may be effected under a hood (40–45° C.); or a tepid wave may be effected (60–80° C.).

Exemplary compounds of general Formula I according to the invention are as follows:

COMPOUND A

S-acetyl mercaptoacetamide having the formula:

(i) Method of production: Into a round-bottomed flask equipped with a stirrer, a thermometer, a reflux condenser and a dropping funnel is introduced one gram-

10 molecule of mercaptoacetamide, and one gram-molecule of acetyl chloride is added drop-wise under stirring, the temperature being maintained between 35° and 45° C. At the end of the operation the mixture is kept stirred for some time, and the hydrochloric acid formed during the reaction is then removed under moderately reduced pressure. The product obtained is then distilled in vacuo. It boils at 132–135° C. under a pressure of 1 mm. Hg. The distilled product crystallises. After recrystallisation from absolute alcohol, a product is obtained which melts at 78–80° C.

The yield is of the order of 85% of the theoretical yield, and analysis of the product gives:

Percent
15 Nitrogen calculated for C ₄ H ₇ NO ₂ S ----- 10.52
Nitrogen found ----- 10.35

(ii) Alternative method of production: Into a round-bottomed flask equipped with a stirrer is introduced 1 gram-molecule of mercaptoacetamide, and 1 gram-molecule plus a 10% by weight excess of acetic anhydride is added drop-wise. The reaction is exothermic. The temperature is maintained at 50° C. by cooling. At the end of the addition, the mixture is heated at 50–60° C. for 1/2–1 hour and then allowed to cool.

The S-acetyl-mercaptoacetamide partly crystallises. The acetic acid formed, and the excess of acetic anhydride, are distilled off in vacuo, and the residue is recrystallised from absolute alcohol or from a mixture of alcohol and benzene. The yield is the same as for method (i) but the product need not in this case be distilled but can be directly isolated.

COMPOUND B

35 *S-acetyl-N-methyl-mercapto-acetamide of the formula:*
CH₃COSCH₂CONHCH₃

40 Into a round-bottomed flask equipped with a stirrer, a thermometer, a condensing device and a dropping funnel is introduced 1 gram-molecule of N-methyl-mercaptoacetamide (HSCH₂CONHCH₃). 1 gram-molecule plus a 10% by weight excess of CH₃COCl is added drop-wise. The reaction being exothermic, the temperature is maintained between 35° and 45° C. by external cooling. The product is thereafter heated for 1/2–1 hour at 50–60° C., to complete the reaction.

45 It is then possible either to distil the product, which boils at 131–134° C. under 3 mm. Hg, or to recrystallise it directly from benzene; it has a melting point of 72° C. The yield calculated from the N-methyl-mercapto-acetamide employed is 71%.

Percent
N calculated for C ₅ H ₈ O ₂ NS ----- 9.52
N found ----- 9.73

55 COMPOUND C

S-acetyl-mercaptopropionamide of the formula:

60 Into a round-bottomed flask equipped with a stirrer, a thermometer, a condensing device and a dropping funnel is introduced a suspension of 1 gram-molecule of α-mercaptopropionamide in 200 cc. of benzene. 1 gram-molecule plus a 10% by weight excess of acetic anhydride is added under stirring. The reaction is only slightly exothermic and no cooling is required. After the end of the addition, the reaction mixture is heated at about 60° C. for 1 hour under stirring.

65 The liquid separates into two layers. The benzene and the acetic acid formed are distilled off and the residue is then distilled. B.P.: 114–119° C/0.7 mm. Yield: 40%. On cooling, the amide crystallises; melting point: 74° C. (after recrystallisation from benzene).

Analysis:	Percent
N calculated for C ₆ H ₈ O ₂ NS	9.52
N found	9.56

COMPOUND D

S-succinyl-mercaptoacetamide (i.e. S- β -carboxypropionyl-mercaptoacetamide of the formula:

1 gram-molecule of mercaptoacetamide and 1 gram-molecule of succinic anhydride are introduced into a round-bottomed flask. The solid mass is vigorously stirred and is heated to form a paste. The temperature rises to 70-80° C. and it is maintained at this level for 1/2-1 hour. The mixture, which is initially pasty, thereafter hardens. Stirring is discontinued and, after cooling and recrystallisation from a mixture of benzene and alcohol, a product is obtained which melts at 117-118° C. Yield: 67%.

Analysis:	Percent
N calculated for C ₆ H ₈ O ₄ NS	7.33
N found	7.03

The following examples will serve to illustrate the process according to the invention. All these examples concern only the operation of curling hair on curlers, that is to say, the operation concerning the softening of the keratin. The subsequent operation for setting the shape imparted to the hair, after rinsing, is carried out in known manner and needs no further information.

EXAMPLE I

A solution having the following composition is prepared in the cold at the time of use:

S-acetylmercaptoacetamide	9
Triethanolamine	12
Water to make 100 cc.	

The hair is impregnated with this solution by the usual method employed in cold waving. The solution is then allowed to act for 10-25 minutes and setting of the hair is carried out in the usual manner. A stable permanent wave is thus obtained.

EXAMPLE II

Under the same conditions as mentioned in Example I, there is applied to the hair a solution having the following composition:

S-acetylmercaptoacetamide	9
20% ammonia	7
Water to make 100 cc.	

This solution is allowed to act for 10-25 minutes, and setting is effected in the usual manner. There is thus obtained a very tight wave.

EXAMPLE III

Under the same conditions as in Example I, there is applied to the hair a solution having the following composition:

N-methyl-S-acetylmercapto-acetamide	10
20% ammonia	9
Water to make 100 cc.	

The hair is then set by the usual method with the aid of an appropriate oxidising agent. An excellent wave is thus obtained.

EXAMPLE IV

Under the same conditions as in Example I, there is applied to the hair a solution having the following composition, prepared immediately before application

G.	
S-succinyl mercaptoacetamide	12.5
(S- β -carboxypropanoyl - mercapto-acetamide) 20%	
ammonia	16.5

5 Water to make 100 cc.

it is allowed to act for 10 to 20 minutes at ambient temperature and, after setting with the aid of a conventional oxidising agent, a permanent wave of good stability is obtained.

10

EXAMPLE V

An aqueous solution containing 8% by weight of S-acetyl mercaptoacetamide and 24% by weight of triethanolamine is applied by the so-called "hood" waving technique. The temperature of the locks of hair is 40-45° C. The solution is allowed to act for 5-10 minutes. A very satisfactory wave is obtained.

EXAMPLE VI

20 An aqueous solution containing 6% by weight of S-acetyl-mercaptoacetamide and 12% by weight of triethanolamine is applied by the so-called "hood" method. The temperature of the locks of hair is 40-45° C. The solution is allowed to act for 10 to 20 minutes, whereby a very satisfactory wave is obtained.

25

EXAMPLE VII

There is applied to the hair by the method usually adopted in the so-called "hood" waving, an aqueous solution containing 9% by weight of S-acetyl-mercaptoacetamide and 12% by weight of triethanolamine, for 8 to 15 minutes. The temperature of the locks of hair is from 40-45° C. An excellent wave is obtained.

EXAMPLE VIII

30 35 There is applied to the hair for 20 minutes by the so-called "hood" waving method an aqueous solution containing 9% by weight of S-acetyl mercaptoacetamide and 7% by weight of 20% ammonia. An excellent wave is obtained.

40

EXAMPLE IX

An aqueous solution containing 5% by weight of S-acetyl mercaptoacetamide and 10% by weight of triethanolamine is prepared. This solution is applied by the usual method for obtaining a so-called tepid wave. The temperature on the locks of hair is 70-80° C. This solution is allowed to act for 5-10 minutes, and the oxidation is then effected in the usual manner. An excellent wave is thus obtained.

45

EXAMPLE X

50 55 Under the same conditions as in Example IX, an aqueous solution containing 5% by weight of S-acetyl-mercaptoacetamide and 15% by weight of triethanolamine is applied to the hair and allowed to act thereon for 5-10 minutes. The temperature on the locks of hair is from 70-80° C. An excellent wave is thus obtained.

60

EXAMPLE XI

An aqueous solution containing 9% by weight of S-acetyl-mercaptoacetamide is prepared and the hair is impregnated therewith. The hair is thereafter wound on curlers and, in a second step, it is saturated with a 10% by weight monoethanolamine solution. After 15 to 20 minutes under a hood, the hair is set and a valuable wave is thus obtained.

65

EXAMPLE XII

70 75 Under the same conditions as described in Example XI, the hair is first impregnated with an aqueous 13% by weight solution of S-succinyl-mercaptoacetamide (i.e. S- β -carboxypropanoyl - mercaptoacetamide) and, after winding of the hair on curlers, it is again impregnated with an ammonical solution containing 11% by weight of 20% ammonia. After contact for 10 to 20 minutes under

a drying hood, and after setting, an excellent wave is obtained.

What we claim is:

1. A freshly prepared composition suitable for application to hair as a step in the permanent waving thereof comprising, in aqueous solution a mercapto derivative of the general formula

where R is a radical selected from the group consisting of a lower alkyl group having from 1 to 3 carbon atoms and a carboxy alkyl group having from 2 to 5 carbon atoms and R₁ and R₂ are members selected from the group consisting of hydrogen and a lower alkyl residue containing from 1 to 3 carbon atoms and a nitrogen base, said composition having a pH within the range of about 5 to 9.5, the amount of nitrogen base being from 1 to 5 moles and preferably of 1 to 3 moles, per mole of mercapto derivative.

2. A process for the so-called permanent waving of hair wherein the hair is impregnated with a freshly prepared aqueous solution of a mercapto derivative of the general formula

where R is a radical selected from the group consisting of a lower alkyl group having from 1 to 3 carbon atoms and a carboxyalkyl group having from 2 to 5 carbon atoms and R₁ and R₂ are members selected from the group consisting of hydrogen and a lower alkyl residue containing from 1 to 3 carbon atoms and a nitrogenous

5

base, said composition having a pH within the range of about 5 to 9.5, the amount of nitrogen base being from 1 to 5 moles, preferably of 1 to 3 moles, per mole of mercapto derivative; restraining said hair to a desired configuration and setting it in said configuration.

3. A composition according to claim 1 wherein the basic substance is ammonia.

4. A composition according to claim 1 wherein the basic substance is an ethanolamine.

5. A mercapto derivative of the general formula

where R is a radical selected from the group consisting of a lower alkyl group having from 1 to 3 carbon atoms and a carboxyalkyl group having from 2 to 5 carbon atoms and R₁ and R₂ are members selected from the group consisting of hydrogen and a lower alkyl residue containing from 1 to 3 carbon atoms.

6. S-acetyl-mercaptoacetamide.

7. S-acetyl-N-methyl-mercaptoacetamide.

8. S-acetyl-alpha-mercaptopropionamide.

9. S-succinyl mercaptoacetamide. (S-β-carboxypropanoyl-mercaptoacetamide.)
